UNITED STATES PATENT OFFICE

CHARLES E. EBERSOL, OF LANSING, MICHIGAN

GAS BURNER AND FLAME GUARD

Application filed June 23, 1930. Serial No. 463,280.

This invention relates to an improved gas burner.

One object of the invention is to provide a gas burner employing a guard for concentrating the flame upon the article to be heated in such a manner that said article will be heated more quickly and maximum efficiency and economy will be obtained from the fuel.

Another object of the invention is to provide a device of this character wherein the guard is spaced above the burner to define an air inlet slot at the lower edge of said guard for admitting air to the outer series of ports of the burner and promoting combustion at said ports while also the guard will tend to produce a heated zone immediately above the burner within the confines of the guard for providing warm air to promote combustion at the ports of the burner as a whole.

A further object of the invention is to provide a gas burner employing a guard which will tend to protect the flame from extinction by drafts of air or by liquids boiling over, thus preventing a waste of fuel and the possible asphyxiation of persons in the vicinity.

A still further object of the invention is to provide a gas burner wherein the burner and guard will function as a unit.

Other and incidental objects of the invention not mentioned in the foregoing will be apparent during the course of the following description.

In the drawings:

Figure 1 is a top plan view of the device partly shown in section,

Fig. 2 is a sectional view on the line 2—2 of Fig. 1 looking in the direction indicated by the arrows,

Fig. 3 is a sectional view showing a modified form of the invention, and

Fig. 4 is an enlarged fragmentary detail elevation showing one of the legs employed in conjunction with the guard.

Referring more particularly to the drawings, the numeral 1 indicates a circular inner distributing pipe or chamber which is substantially elliptical in cross section and is provided with an axial draft passage 2.

Formed on the outer wall of said chamber are radially extending equally spaced burner tubes 3 which are also substantially elliptical in cross section, and formed on the upper walls of said tubes as well as in the upper wall of said chamber are spaced upstanding nipples which are apertured to form raised outlet ports 4. Connecting the outer ends of the tubes and disposed in concentric spaced relation to the chamber 1 is an annular outer fuel distributing pipe or chamber 5 which, like the chamber 1 and radially extending pipes 3, is substantially elliptical in cross section and includes inner and outer walls 6 and 7 and a bottom wall 8. Formed on the wall 7 is an annular shoulder 9 and, as will be observed, the chambers and tubes are somewhat wider at their lower portions than at their upper portions so that air surging upwardly from beneath the burner will have more free access to the ports 4. The circulation of air about the ports is further augmented inasmuch as said ports are raised and thereby define channels between adjacent ports. A better circulation of air will, of course, produce more rapid and efficient combustion. Formed in the wall of the chamber 5 are circumferentially disposed spaced raised ports 10 of a formation similar to that of the ports 4. All of the radially extending tubes communicate at their outer ends with the chamber 5.

Integrally formed on the burner is a mixture inlet pipe 11 offset at its outer end portion to form an enlarged valve head 12 which is provided with openings 13 in the outer end wall thereof. Fitting over the valve head is an air controlling valve 14 having openings 15 formed therein, said valve being rotatable for bringing the openings 13 and 15 into registration for admitting air into the pipe 11. The valve may be rotatably connected with the head in any approved manner. As best seen in Fig. 2 of the drawings, the pipe 11 communicates at its inner end portion with the chamber 1, one of the radially extending tubes, and that portion of the chamber 5 adjacent to the end of said tube. Extending axially through the valve 14 and the valve head 12 and into the pipe 11 is a fuel supply

90

100

pipe 16. Air enters through the openings 13 and 15 and unites with the fuel entering through the pipe 11 to form a combustible mixture, which is usual in burners of this character.

5 Formed on one or more of the burner tubes are notched supporting yokes, a typical one of which is shown at 17, said yokes being adapted to receive a supporting rod or rods 10 17' for maintaining the burner in operative position.

Associated with the outer wall 7 of the chamber 5 is a removable upwardly projecting substantially frusto-conoidal band or 15 flame guard 18. As will be seen more clearly in Fig. 2 of the drawings, the flame guard extends upwardly in a plane with the outer wall of the chamber 5 for a distance substantially half its width and then is curved inwardly. The entire width of the guard 18 is 20 substantially the same as the depth of the burner and the upper rim of said guard is of a diameter slightly less than the diameter of the wall 7 of the chamber 5. Formed on said 25 wall are preferably three spaced triangular seats 19 and carried on the guard are preferably three spaced adjustable rectangular legs 20. Formed in each of said legs is a longitudinally extending slot 21 and extending 30 through such slots and connecting the leg with the guard is a screw 22 which normally clamps the leg in an adjusted position. The legs are, of course, adjusted by sliding them up and down when the screws 22 are loosened, 35 said screws limiting the travel of said legs. The legs normally cooperate with the seats for mounting said guard in adjustably spaced relation above the burner to define an annular air receiving slot 23 which may be varied 40 in width by adjustment of the legs.

As will be readily understood from the foregoing description, when the fuel is introduced and ignited, the flame from the raised ports in the outer distributing chamber 5 and 45 in the outer end portions of the tubes 3 will be deflected inwardly by the guard 18 toward the axis of the draft passage 2 and thus concentrated upon the article to be heated. It is to be further understood that the inlet 50 slot between the guard and burner will facilitate admission of air to the outer series of ports of the burner and thereby promote combustion at said ports, while the guard will, also, tend to produce a heated zone within the 55 confines of said guard immediately above the burner for providing warm air to aid combustion at the ports of the burner as a whole. In view of the fact that the guard extends above the burner for substantially half its 60 depth, the mixture issuing through the ports is completely ignited before it hits the guard so that danger of forming carbon monoxide gas, which would be released if the mixture was permitted to flow against the guard, is 65 prevented. It is clear, of course, that, due

to the relatively large amount of air admitted and the concentration of the flame, a more efficient burner is produced with the use of a less amount of fuel. It is further pointed out that, should liquid being heated 70 in a vessel above the burner be caused to boil over, the guard will tend to deflect such liquid from the flame.

Referring now to the modification of the invention as seen in Fig. 3 of the drawings, 75 the numeral 24 indicates an inner distributing pipe or chamber having radially extending burner tubes 25 formed thereon, and formed in said tubes are spaced raised ports 26. Connecting the outer ends of the tubes 80 and mounted in concentric spaced relation to the chamber 24 is an annular band or wall 27 having a shoulder 28 formed thereon. Associated with the band 27 is a frusto-conoidal guard 29 similar to that employed in the preferred embodiment of the invention. This guard is supported in the same manner as is the guard of the preferred form and aside from the above mentioned particulars, the modification of the invention is identical with 85 the preferred form and functions in like manner.

Having thus described the invention, I claim:

1. A device of the class described including, 95 in combination with a gas burner having a distributing chamber provided with a straight outer wall and fuel outlet ports, a flame guard upstanding from said chamber and formed with a wall having its lower portion disposed to lie in vertical alignment with the straight outer wall of the chamber and its upper portion directed inwardly, means carried by the chamber and flame guard for adjustably connecting said flame guard to 100 said chamber, and a mixture inlet pipe communicating with the chamber.

2. A device of the class described including, 110 in combination with a gas burner having a distributing chamber formed with fuel outlet ports and having a straight wall formed with spaced seats, a flame guard carried on the distributing chamber, spaced legs adjustably mounted on the flame guard, said legs being adapted to cooperate with said seats for supporting the flame guard in an adjusted position on the chamber, and a mixture inlet pipe communicating with said chamber.

3. A device of the class described including, 120 in combination with a gas burner having a distributing chamber formed with a straight outer wall terminating at its upper side in an annular shoulder, said wall having spaced seats formed on its outer surface, a flame guard associated with the distributing chamber and having a wall comprising a straight lower portion and an inwardly directed upper portion, spaced legs mounted on said straight portion of the flame guard and being adapted to cooperate with the seats for 125

mounting the flame guard in position on
the chamber, said legs being shiftable verti-
cally for defining an annular air inlet slot
between the lower edge of said straight por-
tion and the annular shoulder and said guard
being shiftable to overlie said shoulder for
closing the slot.

In testimony whereof I affix my signature.
CHARLES E. EBERSOL. [L.S.]
